UNITED STATES PATENT OFFICE.

HARRY E. KATZENMOYER, OF ROSEDALE, PENNSYLVANIA, ASSIGNOR OF ONE-HALF
TO PATRICK HENRY FISHER, OF WYOMISSING, PENNSYLVANIA.

CIRCULAR-KNITTING MACHINE.

Application filed September 30, 1922. Serial No. 591,517.

To all whom it may concern:

Be it known that I, HARRY E. KATZENMOYER, a citizen of the United States, residing at Rosedale, in the county of Berks and 5 State of Pennsylvania, have invented certain new and useful Improvements in Circular-Knitting Machines, of which the following is a specification.

My invention relates to circular knitting machines, and consists in improved mechanism adapted to simultaneously knit full-circle courses of a main yarn and alternating part-circle courses of a separate yarn, as hereinafter fully described in connection with 10 the accompanying drawings, and pointed out in the appended claim.

Fig. 1 shows in side elevation essential portions of a known type of knitting machine, with my improved mechanism applied 20 thereto.

Fig. 2 is an end elevation of the same looking in the direction of arrow 2, Fig. 1.

Fig. 3 is a plan view with parts omitted.

Fig. 4 is a partial plan view of the sinker 25 ring with the cover plate removed.

Fig. 5 is an inner view of the cam ring developed in a straight plane indicating the paths of the needle butts.

Fig. 6 is a diagrammatic view indicating 30 the arrangements of the needle cylinder.

Figs. 7, 8, and 9 indicate the needles employed.

Figs. 10, and 11 indicate an additional clamp and severing device for the separate 35 yarn.

Fig. 12 indicates a stocking produced by my improved mechanism.

Referring to the drawing 1 represents the frame of the machine, 2 the rotated needle 40 cylinder, 3 the cam ring and 4 the sinker ring of a well known type of knitting machine. The needle ring includes the usual knitting cams 10, 11, 12, and 13 (see Fig. 5), and dividing cam 14 for separating the 45 needles preparatory to reciprocal knitting for the heel and toe portions of a stocking, the needle cylinder having the usual half-circle series of long butt needles 15 and half-circle series of short butt needles 16. Yarn 50 is fed to the needles by a main yarn guide 17 controlled as heretofore from a pattern drum 18 through guide actuating push bar 19, and rotary movements are imparted to

the needle cylinder 2 from main drive shaft 20. The mechanism thus briefly described 55 is well known and its operation in producing a tubular knitted stocking will be readily understood.

In Fig. 12 I have indicated a stocking having a leg portion A, heel pocket portion 60 B, foot portion C, and toe pocket portion D. This is knitted in well known manner by a circular rotation of the machine forming full circle courses, except in the heel and toe, which are formed as usual by reciprocal knitting on the short-butts needles only. In forming the foot portion C it is desirable 65 to make the sole portion C' thereof of greater length than the upper half or instep portion, to produce a better fit, and to this end 70 I introduce in said sole portion C' additional part-circle courses of loops of a separate yarn alternating with the usual full circle courses. And it is the object of my improvements to 75 simultaneously knit these additional part-circle courses of the separate yarn during the usual circular knitting of the foot portion C.

As stated, the sole portion of the foot C' is produced on the short-butts needles, and the 80 sinkers within the ring 4, in the present machine, are divided for another purpose, into half-circle series of different butts corresponding with the needle divisions. To knit additional courses on said short-butts needles 85 16 I provide the cam ring 3, with additional knitting cams 25, 26 and 27 for the latter and add a cam 28 in the sinker ring 4 adapted to move one of the series of sinkers therein corresponding with said short-butts 90 needles into cooperation with said knitting cams so as to form additional courses of loops on the short-butts needles of a separate yarn fed to the latter by a separate guide 95 29. The long butt-needles are prevented from receiving and knitting this separate yarn by an extension 36 of cam 26 which is set back so as to avoid the short butts, but depresses the long butts to pass idly under these knitting cams 25, 26, and 27, as clearly 100 seen in Fig. 5. The result of this cam arrangement is that knitting cams 10, 11, 12 and 13 form continuous full-circle courses of loops of the main yarn during rotation of the machine, and cams 25, 26 and 27 form 105 part-circle courses of loops of the separate

yarn on the short butt needles only, said part circle courses being simultaneously knitted with the full-circle courses and alternating with the latter in the sole portion C' of 5 the foot of the stocking.

The separate yarn extending beyond the short-butt needles merely floats across the cylinder to be afterwards cut away in well known manner. But to securely tie the ends 10 of the same and produce a better finish, I interknit these end portions with the main yarn as in the following manner: I remove two needles at each end of the half circle series of long butt needles 15 and substitute 15 therefore intermediate-length-butt needles 30 having long latches, and provide stitch cam 27 with a set-back extension 31 which does not affect the travel of the short-butt needles, but elevates said intermediate-butt-needles to pass over said cam, their relowering 20 being effected by dividing cam 14 preliminary to their entering the main knitting cams 10, 11, 12, and 13. The effect of such travel of the needles 30 is to actuate them 25 with the short butt needles by means of cams 25 and 26 to engage their hooked ends with the separate yarn fed to the latter. The short butt needles form knitted loops of the separate yarn as stated through action 30 of stitch cam 27, but the needles 30, raised above the latter by extension 31 thereof, merely hold the yarn ends of said separate yarn on their long latches to be knitted with the main yarn as these needles 30 pass 35 through main knitting cams 10, 11, 12, and 13 which latter act upon all the needles in the cylinder.

Dividing cam 14 is operated in the usual manner as heretofore and is normally in lowered position, indicated in Fig. 5, during circular knitting. Additional knitting cams 25, 40 26, and 27 with their extensions 36 and 31 are mounted on a slide block 40, Fig. 3, which is normally retracted by springs 41 so 45 as to jointly withdraw said cams from the path of the needle butts to inoperative position; and they are jointly moved into operative position for action on said needles by means hereinafter described. Sinker ring cam 28 is normally held in retracted position, in ring 4 shown in dotted lines in Fig. 4, by spring pressed lever 45 pivotally mounted at 46 on frame post 47, the upper end of 50 said lever being connected to said cam by a rod 48, and its lever end 49 being actuated as hereinafter described to swing said cam 28 into the path of one series of sinkers to actuate the latter in cooperation with the short butt needles in forming loops on the latter 55 as before described.

The guide 29 for the separate yarn is pivoted at 50 and normally held in raised inoperative position, seen in dotted lines in Fig. 1 by a spring 51, but is adapted to be lowered as later described so as to bring 60

its guide eye 52 into position to feed its yarn to the short butt and intermediate butt needles as previously described.

The additional part-circle courses of the separate yarn in the sole portion of the foot 65 of a stocking are preferably introduced immediately after the completion of the heel portion B, and to automatically accomplish this from the usual pattern drum 18, I provide the latter with a cam 60 adapted to 70 actuate a push bar 61, the latter having an extension 62 directly contacting with the extended end 63 of yarn guide 29 to swing the guide eye 52 of the latter into feeding position. The upper rounded end of the 75 push bar 61 is adapted to contact with the end of the lever 65, pivotally mounted on the frame 1 at 66, to swing the opposite end of the latter into contact with slide block 40 and lever-end 49 so as to jointly actuate 80 both to respectively enter the knitting cams 25, 26, and 27 into the path of the needle butts, and to move sinker cam 28 into cooperative position therewith. This action 85 of the pattern drum 18 thus automatically 90 actuates the several cooperative cams and yarn guide to introduce the separate yarn and form the additional part-circle courses as before described.

To cut off the end of the separate yarn 95 and hold the free end of the latter after completion of the additional part-circle courses until again required in the next stocking, I preferably provide separate cutting and clamping devices for the latter in addition to the usual cutting and clamping devices for the yarn changing guides commonly employed. These separate cutting and clamping devices comprise a shears 70 and clamp 71 actuated by a lever 73, and direct action 100 is imparted to the latter by one of the regular push bars, as bar 19,—a change of yarn 105 commonly being made before knitting of the toe portion D.

My machine operates in the usual manner 110 in the production of a tubular stocking throughout the leg A and the making of the heel portion B; after which latter the pattern drum 18 raises push bar 61 to operate lever 65. Lever 65 turning on its pivot 66 115 contacts with slide block 40 and with lever-end 49 to jointly actuate both,—slide block 40 carrying the separate knitting cams 25, 26, and 27 as heretofore described, and lever end 49 of lever 45 controls the swing of 120 sinker cam 28. And push bar 61 through its extension 62 lowers the separate yarn guide 29 to bring the eye 52 of the latter into feeding position. These movements 125 automatically effected from the pattern drum 18 cause the formation of additional part-circle courses of loops of the separate yarn to be simultaneously knitted on the short butt needles during the usual formation of full-circle courses on all the needles 130

as heretofore described and to tie the ends of said separate yarn by jointly knitting both yarns on needles 30. After completion of the foot portion C with the additional courses in the sole portion C' thereof, the pattern drum 18 releases bar 61 to withdraw the separate knitting cams, sinker cam 28, and yarn guide 29 from operative position, after which the toe pocket portion D is made in the usual manner.

Modifications of the machine above described may be readily devised and I do not desire to limit myself to the specific construction shown, but:

15. What I claim is:

In a circular knitting machine comprising a circular series of needles, a main yarn guide therefor and main knitting cams for

all the needles, an extra yarn guide movable into and out of position for feeding to 20 a part circle series only of said needles, extra knitting cams for the latter movable into and out of the needle path, a sinker ring and a movable cam therein adapted to 25 additionally actuate the sinkers in cooperation with said extra knitting cams, a lever mechanism adapted to actuate said extra yarn guide, a separate lever mechanism adapted to actuate both said extra knitting cams and said extra sinker ring cam, and a 30 pattern controlled push rod jointly operative upon both said lever mechanisms.

In testimony whereof I affix my signature.

HARRY E. KATZENMOYER.
